UNITED STATES PATENT OFFICE

ELMER N. HOCKETT, OF UNIONVILLE, MISSOURI

AUTOMOBILE SIGNAL

Application filed December 22, 1925. Serial No. 77,017.

My present invention pertains to automobile signals constructed with a view to enabling the driver of an automobile to communicate his intentions to a driver behind him; and it contemplates the provision of a signal of simple and inexpensive construction, easy to install, reliable in operation and possessed of the practical advantages hereinafter ascribed to it.

With the foregoing in mind, the invention in all of its details will be fully understood from the following description and claims when the same are read in connection with the drawings, accompanying and forming part of this specification, in which:

Figure 1 is a view diagrammatic in character, illustrating the best practical embodiment of my invention of which I am cognizant.

Figure 2 is an enlarged detail section showing the base of the improvement and the part carried thereby.

Figure 3 is an enlarged detail elevation of the portion of the improvement designed to be carried at the rear end of an automobile.

Similar numerals of reference designate corresponding parts in all of the views of the drawings.

In accordance with the preferred embodiment of my invention, a base 1, preferably of insulating material, is appropriately supported just under and to the left of the steering wheel of an automobile. Carried by the said base are terminals 2, 3, 4, 5, 6, 7 and 8, Figures 1 and 2. The terminals 2, 3 and 4 in connection with a hand lever 9 constitute a three point switch, and by comparison of Figures 1 and 2 it will be noted

that the lever 9 is electrically connected at 10 with a movable bar 11, and that the said connection 10 is connected by a conductor 12 with the terminal 5. The bar 11 is normally maintained in the position shown in Figure

2 by a spring 13, the bar 11 in said position contacting with the terminal 8, and the contact plate 7 α on the button 8 α below the bar 11 being spaced from the terminal 7 and also from the terminal 9 α connected by conductor 10 α with the terminal 8. On the bar 11 is a

finger piece 14 by which it may be moved against the action of the spring 13 to enable the plate 7 α to electrically connect the terminals 7 and 9 α . Manifestly, however, when the bar 11 is relieved of pressure, the spring 13 will operate to promptly return the bar 11 to its position in contact with the terminal 8. The horn button 8 α is movable in a pedestal guide 11 α and superposed upon a spring 12 α as shown in Figure 2.

At 14 α in Figure 1, is a source of electric energy, one side of which is grounded at 15 and the other side of which is electrically connected at 16 to the terminal 8. Electrically connected at 19 with the terminal 7 is an electric horn 20, grounded at 21. From this it follows that when the conductive bar 11, possessed of resiliency, is depressed, and the button 8 α is moved downwardly by the same, the horn 20 will be supplied with current and sounded; also, that when the bar 11 is in contact with the terminal 8 and the button 8 α is in raised position, the horn 20 will be silent.

The portion of my improvement to be carried at the rear end of an automobile is in the form of a unit as shown in Figure 3, the said unit including a body 30, a central compartment 31, and compartments 32, 33, 34 and 35 grouped about the central compartment 31 and spaced apart so as to present a general cruciform appearance. The compartment 32 is a red light compartment, the same being brought about by preference by the employment of a red lens 32 α , while the compartments 33, 34 and 35 are blue light compartments being so characterized by the employment of blue lenses 33 α as shown conventionally in Figure 1.

The incandescent electric lamp 36 of the compartment 32 is grounded at 37 and is electrically connected at 38, Figure 1, with the terminal 6. Thus when the switch member 38 α is moved into contact with the terminal 5, the filament of the lamp 36 will be caused to glow, the switch at 38 α being provided in order that the compartment 32 may be readily put in and out of commission. Manifestly when the switch member 38 α is in contact with the terminal 5 current will pass

from the source of energy through the conductor 16, the terminal 8, the conductive bar 11, the conductor 12, the terminal 5, the switch member 38 α , the terminal 6 and the conductor 38 to the filament of the lamp 36 and from the said filament to the ground at 37. From this it follows that when the compartment 32 is in commission, and the horn 20 is sounded by the depression of the bar 11, 10 the glowing of the filament in the lamp 36 will be stopped, and that said glowing will be re-established when the bar 11 is released to stop sounding of the horn. Manifestly by the means described the horn may be 15 sounded and the lamp 36 put on and off by the same means, viz; the bar 11 in a manner calculated audibly and visually to attract the attention of a following motorist.

The lamp 41 is to serve secondarily for the 20 illumination of a license plate designated by 40 and relatively arranged as shown in Figure 1. The lamp 41 is grounded at 42, and its filament is connected by a conductor 43 with a switch terminal 43 α , the complement 25 44 α of which is connected by conductor 45 α with the terminal 8. Thus in the night time the lamp 41 may be maintained in commission.

The lamp of the compartment 33 is designated by 50, that of the compartment 34 by 51, and that of the compartment 35 by 52. The filament of the lamp 50 is electrically connected to the ground by the conductor 53, and said filament is connected by a conductor 54 with the terminal 4. Thus when the lever 9 contacts with the terminal 4 the lamp 50 will be caused to glow for the purpose of indicating the intention of the driver to make a left turn. The filament of the 30 lamp 51 is grounded at 60, and is electrically connected by a conductor 61 with the terminal 3. Thus when the lever 9 is in contact with said terminal 3, the filament of the lamp in the compartment 34 will be caused to 35 glow, and the intention of the driver of the automobile to proceed forwardly will be made patent. The filament of the lamp 52 complementary to the compartment 35 is grounded at 40 70 and is connected by a conductor 71 with the terminal 2. From this it follows that when the lever 9 is moved into contact with the terminal 2, the filament of the lamp 52 will be caused to glow, and hence the compartment 35 will indicate the intention of the 55 driver to make a right turn.

The blue lights of compartments 33, 34 and 35 in association with the central red tail light and the pendent red stop light will serve to enhance the appearance of an automobile 60 in the night time, and the said blue lights are also advantageous inasmuch as they will not give rise to any glare.

It will be understood from the foregoing that when the driver of an automobile 65 equipped with my improvement wishes to

make a left turn and then stop, he is enabled to indicate his intentions by moving the lever 9 to the terminal 4 and snapping on the stop lamp 36 at the point 5, and then by alternate pressure of and the removal of pressure from the finger piece 14, he may bring about flashing of both of the lamps 36 and 50 and sounding of the horn, thereby signalling a following motorist in a manner that cannot be mistaken.

As will be understood from Figure 3, the compartments 33 and 35 are arranged above the horizontal center of the body 30, to afford ample space for the proper illumination of the license plate or number plate 40. 70 The red light of compartment 31 is preferably brought about by the employment of a red lens, and therefore for the adequate illumination of the license or number plate 40, I provide in the shell of the compartment 31 a mica covered or otherwise appropriately covered opening 75, said opening 75 being so disposed as to direct a beam of light laterally over the face of the plate 40.

In accordance with my invention the red 90 tail lamp 41 when put into commission will glow steadily at all times, and in this connection I would have it further understood that the blue light compartments 33 and 34 and 95 35, and the pendent red stop light compartment 32 are all intended to be used in the day time as well as in the night time.

I would also have it understood that the spaces of the said unit between the compartment 34 on the one hand, and the compartments 33 and 35, on the other, are occupied with an appropriate filling which may be of any description compatible with the purpose of my invention.

It will be apparent from the foregoing that 105 by virtue of the visual and audible means comprised in my invention, the driver of an automobile will be enabled to adequately inform a following driver of intentions with respect to stopping and proceeding forwardly 110 with the equipped automobile and the turning of the same either toward the left or toward the right.

It will also be appreciated that notwithstanding its practical advantages as set forth, 115 my improvement is simple and inexpensive and is susceptible of being installed on an automobile at small expense.

The embodiment herein disclosed constitutes the best practical embodiment of my 120 invention that I have as yet devised. I do not desire, however, to be understood as confining myself to the specific construction and relative arrangement of parts as illustrated and described, my invention being defined by 125 my appended claims within the scope of which changes in construction and arrangement may be made without departure from my invention.

Having described my invention, what I 130

claim and desire to secure by Letters Patent,
is:—

1. In an automobile signal a plurality of signal lamps and a source of current, a horn, 5 circuits and selective switching means for including any of said lamps in circuit with the source of current, said means also including switching means having a circuit closing member biased to a closed circuit position for 10 opening the selected circuit and for thereafter closing the horn circuit.
2. The combination in an electric automobile signal, of a source of electric energy, an electric horn, a base, a terminal electrically 15 connected with the source of energy and carried by said base, a terminal carried by the base and electrically connected with the horn, a conductive manually movable member normally maintained in yielding manner in contact with the source of energy terminal and movable out of said contact, means whereby when said conductive member is movable out of contact with the source of energy terminal electric connection is effected between the 20 source of energy terminal and the terminal electrically connected with the horn, left and right electric lamps, terminals electrically connected with said lamps, and a single conductive lever electrically connected with said 25 30 manually movable conductive member and movable into contact with the lamp terminals selectively; said lamp terminals and lever being also carried by said base.

In testimony whereof I affix my signature.
